Primary Examiner — Bridget L Eland*(74) Attorney, Agent, or Firm* — Sheridan Ross P.C.**CLAIM**

The ornamental design for a spinal distraction instrument, as shown and described.

DESCRIPTION

FIG. 1 is a front perspective view of a spinal distraction instrument showing my new design;

FIG. 2 is a rear perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.
